ONE-PIECE GARMENT

Joseph Weingarten, Bronx, N. Y.

Application April 29, 1944, Serial No. 533,299

2 Claims. (Cl. 2—80)

1

The invention relates to one-piece garments and more particularly to protective garments for children as exemplified for instance by the so-called snow suits.

The object of the invention is to provide a one-piece garment constructed in a novel manner to present the appearance of a two-piece garment including a coat.

The invention contemplates further a one-piece garment of the type indicated which is good-looking when worn and provides adequate protection and warmth for the wearer, and which is easily put on and removed at will.

Other objects will appear from the description hereinafter and the features of novelty will be pointed out in the claims.

In the accompanying drawing, which illustrates an example of the invention without defining its limits,

Fig. 1 is a front view of the novel garment as it appears when closed;

Fig. 2 is a rear view of said garment;

Fig. 3 is a front view of the garment as it appears when open for putting it on and removing it from the wearer;

Fig. 4 is a front view of the garment in a partly closed condition;

Fig. 5 is a similar view showing the garment closed to a further extent, and

Fig. 6 is a side view of the novel garment.

Generally speaking the novel garment comprises a lower section and an upper section integral therewith and constructed of any suitable fabric or other material.

The lower section includes leg members which in the illustrated example consist of rear pieces 10 of material and united with front pieces 11 of material along outer seams 12 and similar inner seams to the crotch 13. From the latter upward the rear pieces 10 are connected with each other along a center seam 14 to form the middle or waist portion of the garment. The rear pieces 10 are continued upwardly in the form of back pieces 15 connected with each other along the center seam 14 as shown in Fig. 2 to form the back of the upper section of the garment. Suitable sleeve members 16 may be combined with the back pieces 15, for instance, along the seams 17 as illustrated in Fig. 2 or in any other suitable manner, said sleeve members 16 being provided with elastic cuffs 18 designed to hug the wrists for warmth if desired. In such case, the leg members may be also provided with elastic cuffs 19 designed to hug and enclose the

2

ankles of the wearer for warmth and for excluding snow, moisture and the like.

The front members 11 are connected with each other along a seam 20 and are continued upwardly in the form of integral members 21 united with each other by the seam 20 and together constituting a tongue which comprises a foldable extension of the leg members at the front of the garment. The latter in addition includes co-operating coat members 22 connected with the back pieces 15 along seams 12' which form upward continuations of the outside leg seams 12, as shown in Fig. 6. The coat members 22 further are connected with the sleeve members 16 along seams 23 and are so embodied in the garment as to have their lower edges a relatively free and loose as shown in the illustrated example. The coat members 22 are dimensioned to extend over and cover the tongue 21, 21 when the latter is in its operative position and are provided with co-operating fastening devices such as buttons 24 and buttonholes 25 whereby said coat members 22 may be secured in detachable connection with each other over the aforesaid tongue to present the appearance of a closed coat. Suitable means may be provided for detachably maintaining the tongue 21, 21 in its raised position, as for instance by providing said tongue with buttonholes 26 for engagement with buttons 27 suitably secured to the upper part of the garment as shown in the drawing.

Obviously, the buttons and buttonholes illustrated and described as fastening devices for the coat members 22 and the tongue 21, 21, respectively, may be replaced by other types of fastening means whereby these elements may be detachably secured in place. The garment may also include a conventional collar 28 fastened in place in any conventional manner.

In the normal condition when the garment is open the coat members 22 are disconnected from each other and folded to an open position as shown for instance in Fig. 3, while the tongue 21, 21 may occupy its downwardly folded position as also shown in Fig. 3 to thereby enable the garment to be easily put on or removed from the wearer. After the garment has been donned by the wearer the tongue 21, 21 may be folded upwardly in upright relation to the lower section of the garment so as to cover the upper body and chest of the wearer and secured in this position by connecting the buttonholes 26 with the buttons 27 or by connecting other equivalent types of fastening means which may be provided. The coat members 25 may then be folded over

said upright tongue 21, 21 in external relation thereto to simulate a coat and may be secured in detachable connection with each other over the tongue 21, 21 by means of the buttonholes 25 and button 26, or equivalent fastening means. If desired, the garment may include a belt or tape 29 suitably embodied in the garment at the waist-line and adapted to be tied about the waist of the wearer in the form of a bow knot 30 as shown in Fig. 1 of the drawing. To further add to the 10 ornamental appearance of the garment the latter may be gathered or Shirred at the back about the waist line as indicated at 31 in Fig. 2.

To remove the garment from the wearer, the 15 bow knot 30 is untied to release the band or tape 29 after which the buttons 24 and buttonholes 25 are detached from each other to permit the coat members 22 to be folded to open positions and the tongue 21, 21 to be released by detaching the buttonholes 26 from the buttons 27 and then folded downwardly to the position illustrated in Fig. 3. At this stage the garment may be readily removed from the wearer as will be apparent.

The novel combination garment is ideally 20 adaptable for use as a protective garment, particularly for children, and when worn in the closed condition illustrated in Fig. 1 provides a maximum of protection for the wearer against snow, sleet, rain and the elements in general. When worn the garment presents an attractive 25 and ornamental appearance and gives the impression of being a two-piece suit consisting of a lower leg section and an upper coat section.

While the novel garment is particularly adaptable for use as a so-called snow suit it obviously 30 may be used with equal efficiency for other types of garments designed for children and even for adults. The garment may be made of fabrics or other suitable materials and may easily be removed and put on by children or adults, as the 35 case may be.

Although the present invention has been 40 described in conjunction with a preferred embodiment,

ment, it is to be understood that modifications and variations may be resorted to without departing from the spirit and scope of the invention, as those skilled in the art will readily understand. Such variations and modifications are considered to be within the purview and scope of the claims.

I claim:

1. A one-piece garment comprising a lower section including leg members, a tongue foldably connected with said lower section at the front thereof dimensioned and foldable in upright relation to said lower section to cover the upper body and chest of the wearer, an upper section connected with said lower section and including a back and sleeve members, co-operating coat-members foldably associated with said upper section and extending below the waist line at the front of the garment in detached relation thereto, 20 said coat-members being foldable over said upright tongue in external relation thereto to simulate a coat, co-operating means on said upper section and said tongue for detachably securing the latter in its upright position, and means for securing said coat-members in detachable connection with each other externally over said tongue.

2. A one-piece garment comprising a lower leg section, an upper section integrally combined with said lower leg section, a tongue foldably associated with said leg section at the front thereof dimensioned and foldable in upward relation thereto to cover the upper body and chest of the wearer, means for detachably maintaining said tongue in its upright position, coat-members foldably associated with said upper section and externally foldable over said tongue, said coat-members extending below the waist line in detached relation to said lower leg section to simulate a coat, and means for securing said coat-members in detachable connection with each other externally over said tongue.

JOSEPH WEINGARTEN.
